LEWIS C. MYERS, OF NEW YORK, N. Y., ASSIGNEE TO ROYAL TYPEWRITER COMPANY, OF NEW YORK, N. Y., A CORPORATION OF NEW JERSEY.

SPRING-BARREL MECHANISM FOR TYPE-WRITING MACHINES.

1,072,149.

Specification of Letters Patent.

Patented Sept. 2, 1913.

Application filed June 12, 1908. Serial No. 501,693. Renewed January 29, 1913. Serial No. 745,607.

To all whom it may concern:

Be it known that I, Lewis C. Myers, a citizen of the United States of America, residing in the borough of Brooklyn, city and State of New York, have invented certain Improvements in Spring-Barrel Mechanism for Type-Writing Machines, of which the following is a specification.

The general purpose of this invention is to provide simple and effective means for assembling the spring barrel.

In the accompanying drawings: Figure 1 is a detail side elevation partly in section showing one form of the device; Fig. 2, an elevation of the right hand side of Fig. 1; Figs. 3, 4 and 5 are detail views of the respective parts of the composite spring barrel shaft; Fig. 6, a section on line 6, 6, of Fig. 1; Fig. 7, a side elevation showing a modified construction; Fig. 8, an elevation from the left hand side of Fig. 7; Figs. 9, 10 and 11 are detail views of the respective parts of the composite spring barrel shaft employed in the construction indicated in Figs. 7 and 8; Figs. 12, 13 and 14 are detail views of the respective parts of a composite spring barrel shaft of still another construction.

Reference will first be made to the construction disclosed in Figs. 1 to 6 inclusive. 1 is the ribbon driving shaft carrying a loose pinion 2 meshing with a driving gear 3 of the spring barrel. The pinion 2 is connected with the shaft through a ratchet 4 formed on the hub integral with the wheel and engaged by a spring pressed pawl 5 contained in a cup or housing attached to the end of the shaft. By this means, the ribbon is driven during the forward movement of the carriage but the shaft 1 remains at rest during the return movement. 7 is the casing or barrel of a spring drum at one side of which is secured the driving gear 3. The spring barrel shaft is composed of two members 8 and 9. The part 8 is of two diameters and at that end of larger diameter there is secured a worm gear 10. The part 8^a of reduced diameter has adjacent the shoulder formed by the part of the larger diameter a cross pin 8^b. The other part 9 of the shaft has a central hub 9^a on the periphery of which is a hook 9^b to receive the inner end of the coiled motor spring. At each side of the hub 9^a, the shaft is of reduced diameter. One reduced part 9^c has a dia-

metrical slot 9^d in its end and the other 9^e has in it a threaded aperture 9^f. When assembled as in Fig. 1 the part 9 is slipped over 8^a, the cross pin 8^b entering slot 9^d and locking together the two members of the shaft, and the hub 9^a lies within the cover or casing 7. One end of the coiled spring is attached to the hook 9^b and the other end to the interior of the casing 7. The end of the part 8^a which has been passed through the sleeve 9 is mounted in a suitable bearing 11 in a bracket 11 while the other end just inside of the worm gear 10 has a bearing in another bracket 12. A collar 13 encircling the part 9^e of the member 9 is held in position by a set screw passing through the collar and into the threaded aperture 9^f in the part 9^e. An adjustable worm 18 turning in a bearing in bracket 12 engages the worm gear 10 and affords a means of ready adjustment of tension of the spring barrel. 20 indicates the ordinary draw tape extending from the spring barrel to the carriage.

The construction shown in Figs. 7-14 inclusive will now be described. The parts of the composite shaft are shown in Figs. 9, 10 and 11. They are the same as shown in Figs. 3, 4 and 5 except that the part 8^a is reduced in length as also is the part 9^e. There is the same cross pin 8^b adapted to engage a slot 9^d. In addition to the slot 9^d in the part 9^e there is also at right angles to the slot a tapped aperture 9^f to receive a screw bolt 21 (Fig. 7) passing through a collar 22. The shaft in this construction is not extended beyond the spring barrel as the ribbon is to be differently driven. In Fig. 7, there is a stud shaft carrying at one end a bevel gear 23 adapted to intermesh with a gear through which the ribbon mechanism is actuated and on the opposite end of the shaft there is a ratchet wheel 24 driven by a spring pressed pawl 25 rocking about a pin in the side face of the spring barrel. The adjustment is effected by worm and gear devices in the manner already described. Figs. 7-14 show the devices as adapted to a machine differing somewhat in general construction from that to which the devices of Figs. 1 to 6 inclusive are adapted.

Figs. 12, 13 and 14 show a modification. Instead of employing the reduced circular portion 8^a of the composite shaft that part of it marked 8^c (Fig. 12) is square in cross section and the bore of the sleeve 9 is corre-

105

110

spondingly shaped. Otherwise the construction is in all respects the same as that indicated in Figs. 9, 10 and 11.

I claim:

- 5 1. Spring barrel mechanism for a type-writing machine, comprising a two-part shaft, one part in the form of a sleeve centrally enlarged circumferentially and having on said enlargement a means for attachment of the inner end of the spring and having a transverse notch in one reduced end, and an aperture in the other; and the other part a rod fitting within the sleeve and having a transverse projection fitting in said notch in the end of the sleeve; a collar on the other end of the sleeve and a screw passing through said collar and the aperture in one end of the sleeve.
- 10 2. Spring barrel mechanism for a type-writing machine comprising a two-part shaft, one part in the form of a sleeve centrally enlarged circumferentially and having on said enlargement a means for attachment of the inner end of the spring and having a transverse notch in one reduced end, and an aperture in the other; and the other part a rod fitting within the sleeve and having a transverse projection fitting in said notch in the end of the sleeve; a collar on the other end of the sleeve and a screw passing through said collar and the aperture in one end of the sleeve.
- 15 3. Spring barrel mechanism for a type-writing machine, comprising a two part shaft, one part in the form of a sleeve centrally enlarged circumferentially and having on said enlargement a means for attachment of the inner end of the spring, the reduced end portions of the sleeve serving as a support for the spring barrel and upon which it may rotate, the other part a rod fitting within the sleeve and connected thereto to turn therewith. 35
- 20 4. Spring barrel mechanism for a type-writing machine, comprising a two part shaft, one part in the form of a sleeve centrally enlarged circumferentially and having on said enlargement a means for attachment of the inner end of the spring, the reduced end portions of the sleeve serving as a support for the spring barrel and upon which it may rotate, the other part a rod fitting within the sleeve and connected thereto to turn therewith, the rod terminating in one end in a worm for adjusting the interlocked rod and sleeve independently of rotation of the spring barrel. 45
- 25 5. Spring barrel mechanism for a type-writing machine comprising a two-part shaft, one part in the form of a sleeve centrally enlarged circumferentially and having on said enlargement a means for attachment of the inner end of the spring and also having an aperture; and the other part a rod fitting within the sleeve, the sleeve and rod respectively being formed with interlocking means that unite them for rotation, a collar on the sleeve and a screw passing through the collar and into the aperture in the sleeve. 50
- 30 6. Spring barrel mechanism for a type-writing machine comprising a two-part shaft, one part in the form of a sleeve centrally enlarged circumferentially and having on said enlargement a means for attachment of the inner end of the spring, the reduced end portions of the sleeve serving as a support for the spring barrel and upon which it may rotate, the other part a rod fitting within the sleeve and connected thereto to turn therewith, the rod terminating in one end in a worm for adjusting the interlocked rod and sleeve independently of rotation of the spring barrel. 55

In testimony whereof, I have hereunto subscribed my name.

LEWIS C. MYERS.
